(Cl. D15—8)

To all whom it may concern:

Be it known that I, Howard N. Math, a citizen of the United States, residing at New York city, in the county of Bronx and State of New York, have invented a new, original, and ornamental Design for a Prayer Rail or Similar Article, of which the following is a specification, reference being had to the accompanying drawing, forming part thereof.

In the drawing:

Fig. 1 is a rear view of a prayer rail showing my new design;

Fig. 2 is a top plan view thereof; and

Fig. 3 is a side elevational view thereof.

I claim:

The ornamental design for a prayer rail or similar article, as shown.

HOWARD N. MATH.
